UNITED STATES PATENT OFFICE.

HAROLD BROWN, OF KANSAS CITY, KANSAS, ASSIGNOR TO PETER NORDWALL, OF KANSAS CITY, KANSAS.

COMBINED LOCK AND LATCH.

Application filed August 23, 1923. Serial No. 659,021.

To all whom it may concern:

Be it known that HAROLD BROWN, citizen of the United States, residing at Kansas City, in the county of Wyandotte and State of Kansas, has invented certain new and useful Improvements in Combined Locks and Latches; and he does hereby declare the following to be a full, clear, and exact description of the invention, such as will enable others skilled in the art to which it appertains to make and use the same.

This invention relates to a combined lock and latch which will be so constructed that when the same is set it will be impossible for a key to be inserted into the lock from the outside of the door to withdraw the key bolt of the said lock.

An object of the invention is to provide an element for automatically controlling the latch bolt, closing the key hole in the lock so that a key cannot be inserted until the latch bolt is manually retracted to inoperative position by said element, which at the same time uncovers the key hole.

Another object of the invention is to provide a combined lock and latch which will be springless and which will be highly efficient in use and quite inexpensive to manufacture.

Other objects will appear as the description proceeds.

In the accompanying drawings which form a part of my application,

Fig. 1 is a side elevation of my improved lock and latch, showing one cover plate for the same removed and the several elements in locked position.

Fig. 2 is a similar view as illustrated in the Fig. 1, but showing the several elements in the unlatched position.

Fig. 3 is a side elevation of my improved lock and latch with one cover plate removed, showing the several elements spaced apart to bring out the overlapping relation of the weight and guard members.

Fig. 4 is a sectional view taken on the line 4—4, Fig. 3.

Like characters of reference are used throughout the following specification and the accompanying drawings to designate corresponding parts.

I employ the usual form of lock case 1, which is provided with the several spaced

lugs 2 to hold the opposite cover plates in spaced relation.

A key bolt 3 is reciprocally mounted in 55 the case 1 on the pin 4 which extends up through the substantially U-shaped slot 5 formed through the said key bolt. The opposite or upper ends of the slot 5 retain the bolt 3 in its locked or unlocked position until the rear end of the bolt is raised by the key 6, the operation of which will be hereinafter described. A notch 7 is cut in the lower side of the key bolt 3 and is adapted to cooperate with the said key 6 to slide the 65 bolt forwardly and rearwardly.

A latch bolt 8 is mounted in the upper portion of the case 1 and is automatically held in outward position by means of the weight 9 which is loosely mounted on the 70 hub 10 which is journaled in the sides of the case, and which is provided with an inner portion 11, which in turn is perfectly connected with the rear end of the latch bar by means of the pin 12.

Guard member 13 is affixed to the hub 10 and turns therewith when the spindle 14 for the knobs 15 is in position. The upper and outer corners of the weight and guard member are notched as at 16 and 17 and are adapted to cooperate with the head or 80 latched portion of the latch bolt 8 when the same is in extended position.

A combined cam 18 and detent 19 are formed integrally and are rotatably mounted on the shaft or pin 20 which is positioned between the side plates of the lock case. An operating knob 21 is adapted to be passed through an opening in the inner side plate of the lock case and to engage the shaft of pin 20 so that the cam and 90 detent may be manually rotated. The several elements of the lock are shown in locked position in Fig. 1 of the drawings and the detent 19 is shown in engagement with the shoulder 22 on the lower and inner end of 95 the weight member 9. The weight member is furthermore notched out as at 23 and is adapted to cooperate with the cam 18 so that when the same is rotated the said weight and guard members will be raised 100 together until they assume the position as best illustrated in Fig. 2 of the drawings whereupon the detent will contact with the stop pin 24 and the guard member 13 will

be withdrawn from over the key hole 25 so that the key 6 may be placed therein and turned to withdraw the key bolt, thereby unlocking the door. When the cam 18 and 5 detent 19 are in the position shown in Fig. 1 of the drawings it will be impossible to turn the door knobs 15 to unlatch the door, but as soon as the cam and detent are turned to the position in Fig. 2 of the drawings 10 the door knobs may be turned to raise the weight and guard members and also retract the latch bolt.

From the foregoing description it will be apparent that I have provided an improved 15 combined lock and latch which will be positively burglar proof as long as the cam and detent are in position as illustrated in Fig. 1 of the drawings, thereby locking the guard member over the key hole, thereby preventing 20 the inserting of a key into the same from the outside of the door. Many minor changes in detail of description may be resorted to without departure from the spirit of the invention.

25 Having thus described my invention what

I claim as new and desire to secure by Letters Patent of the United States is:

1. A device of the character described having a key hole therein, a hub journaled in said case, a guard member fixed on said hub to turn therewith, a cooperating weight loosely mounted on said hub and overlying said guard member, a latch bolt slidably mounted in said case and connected with said weight, a key bolt slidably mounted in said case and being provided with means to limit its inward and outward movement and an integrally formed cam and detent adapted to cooperate with said weight to permit of the movement of the several elements or to hold the same in locked position substantially as described.

2. A device of the character described, comprising a combination as claimed in claim 1, a removable manually operated means for operating said integrally formed cam and detent.

In testimony whereof I affix my signature.

HAROLD BROWN.
